UNITED STATES PATENT OFFICE.

WILLIAM PODMORE, OF PORTHILL, STOKE-UPON-TRENT, ENGLAND, ASSIGNOR OF
ONE-HALF TO HENRY LEWIS DOUTLTON, OF LONDON, ENGLAND.

LATHE.

1,309,046.

Specification of Letters Patent.

Patented July 8, 1919.

Application filed November 8, 1915, Serial No. 60,405. Renewed April 14, 1919. Serial No. 290,109.

To all whom it may concern:

Be it known that I, WILLIAM PODMORE, a subject of the King of Great Britain and Ireland, and resident of Porthill, Stoke-upon-Trent, England, have invented new and useful Improvements in Lathes, of which the following is a specification.

This invention refers to apparatus or machinery for shaping clay while in an unbaked state, and it relates in particular to machines of the kind designed to effect the external shaping (profiling) of the clay blanks of telegraph insulators and the like.

The object of the invention is to provide a construction of machine in which the clay blanks, after being internally bored and after the smaller boring in the head of the blank has been screw-threaded, may be placed and readily and accurately turned up or shaped to the required external profile.

A further object is to provide a machine in which the shaping tools are of a simple character, and do not call for any delicate or elaborate adjustment to insure their accurate operation, the whole machine being such as to allow of its being worked by unskilled labor, and to be easily altered or adjusted to suit the various shapes and sizes of insulators to be produced.

Upon the accompanying drawings,

Figure 1 illustrates a front elevation (partly sectional) and

Fig. 2 is a plan of the improved machine, certain of the parts in Fig. 2 being shown in a position different from that shown in Fig. 1.

Fig. 3 illustrates a further plan view, with certain of the parts in a position different from that shown either in Fig. 1 or Fig. 2.

Fig. 4 illustrates a plan view of a detail part of the machine, embodying a modification hereinafter described.

Fig. 5 illustrates a transverse sectional elevation of the machine on line $v-v$ of Fig. 1, looking from the right hand end of the machine.

Fig. 6 illustrates a like view on line $w-w$ of Fig. 2.

Figs. 7 and 8 illustrate further transverse sectional elevations on lines $x-x$ of Fig. 2

and $y-y$ of Fig. 3 respectively. In these several views (Figs. 5 to 8) the tools are shown in their different operative and non-operative positions.

Figs. 9, 10 and 11 illustrate plan views (to a larger scale) of the several tools, and an insulator blank, the three views also showing the manner in which the tools operate successively in effecting the desired shaping operations.

Fig. 12 illustrates a plan and Fig. 13 a front elevation of a modification hereinafter described.

According to the invention, the improved machine comprises a lathe head-stock a , with shaft b fitted with variable speed pulleys c . The shaft b extends beyond the end of the head-stock, and is provided with a screw threaded part b^1 , the thread of which corresponds with that of the thread of the smaller boring of the insulator blank, and that of the rod by which the finished insulator will eventually be supported. Carried by, and preferably formed in one with the shaft b , is a flanged sleeve d , over which the "skirt" or outer part of the insulator blank will fit when placed on the screwed part of the shaft b , see Fig. 1, the end of the said shaft part coming against the flanged end of the sleeve d when the screw thread has fully entered the boring, and thereby preventing any further endwise traverse of the insulator blank. Between the sleeve and shaft is an annular space in which the central pipe portion of the insulator may lie when on the shaft.

To the rear of the said shaft b is arranged a rod e supported rotatably and slidably in bearing brackets f^1 , f^2 . At or near one end, such rod is provided with a handle g , and at the other end it is connected by a cord or chain h , working over a pulley i , to a small weight j sufficient to overcome the friction of the rod in its bearing brackets. For a portion of its length between the brackets f^1 , f^2 , the shaft e is formed square and wider than at the other parts, and upon such square and wider part, see Figs. 2 and 5, is adjustably fixed a flat metal profiling tool k .

This profiling tool consists preferably of a piece of sheet steel, the forward edge of

which corresponds in shape to the initial profile to be imparted to the insulator.

Also secured to top face of the square part of the rod *e*, see Figs. 6 and 10, is a block *l* to which is fixed a loop-like scalloping tool *m*. This tool is intended to remove the bulk of the surplus clay in advance of the tool *k*, which latter is designed to impart the required finished cylindrical shape to the body part of the insulator and the usual conical shape to the head part of the insulator.

To the rear face of the rod *e*, see Figs. 8 and 11, is adjustably fixed a bracket *n*, to which is secured a further scalloping tool *o*, designed to form the usual "neck" in the insulator.

Immediately below the level, and slightly to the rear of the rod *e*, is a bar or rail *p* supported at each end by the brackets *f*¹, *f*².
20 To the rod *e* on three sides of its square part, are secured three narrow strips of metal or arms *q*¹, *q*², *q*³, these arms, in conjunction with the rail *p*, serving to limit the angular movements of the tools, and the rail *p* acting as a guide for the tools *k* and *m*, as they are moved endwise against the work.

With the rod *e* holding the tool *k* horizontal, the position of the arms *q*¹, *q*², *q*³ is as follows: The arm *q*¹ is secured to the top 30 face of the rod and projects rearwardly, the arm *q*² is secured to the underside of the rod and projects forwardly, while the arm *q*³ is secured to the rear vertical face of the rod and projects downwardly. The arms 35 *q*¹, *q*² lie preferably one over the other, and the arm *q*³ at a point nearer the tool *m*, see Fig. 1.

In the rail *p* and near to the bracket *f*² is a gap *p*¹, see Fig. 1. Through this gap may 40 pass the arm *q*³ when brought opposite the gap.

The said rod *e* and rail *p* are of a length, and the brackets *f*¹, *f*² lie at a distance apart sufficient to allow the tools to be moved endwise toward the bearing *f*² and to a position 45 where they will lie clear of the work.

In proceeding to shape and finish an insulator, the already bored and tapped insulator blank, is placed on the shaft *b* and sleeve *d*, the inner pipe of the insulator blank first fitting the plain and enlarged part *b*¹ of the shaft which (as shown) extends a slight distance beyond the end of the sleeve, and then the "skirt" part fitting the sleeve *d*, so that 50 the blank is concentrically supported before the smaller screwed boring in the head of the insulator engages the screw-thread of the shaft. With the shaft *b* then set in motion, and the insulator blank held stationary 55 by hand, the insulator blank screws on to the shaft until the end of the "skirt" part meets the flange *d*¹ when the blank is released and allowed to rotate with the shaft. By means of the handle *g* the operator then

operates the rod *e* to bring the tools *k*, *m* 65 to the horizontal, the gap *p*¹ in the rail *p* allowing the arm *q*³ to pass the rail and to take up a position behind and against the rear face of the rail. The operator then slowly moves the rod *e* endwise and the scalloping tool *m* against the insulator blank. 70 As the scalloping tool is fed sidewise across the face of the insulator blank while the latter is rotating, see Fig. 6, it serves to remove the bulk of the surplus clay and to give the 75 preliminary rough shaping to the body part of the insulator blank. With the endwise movement of the rod *e* continued, the tool *k* acts upon the blank, see Fig. 7, and imparts to the body part of the blank a true 80 parallel-sided shape. Just prior to completing its full endwise movement, the inclined or diagonal edge *k*¹ of the tool *k* engages the clay and imparts a conical shape 85 to the end or head part of the blank, see Fig. 85 10. The right angled edge *k*² of the tool also trims up the top end face of the insulator blank. This being done, the operator draws back the rod *e* until the end of the square 90 part of the rod meets the bracket *f*², when the arm *q*³ comes opposite the gap *p*¹ in the rail *p*.

The operator then rotates the rod *e* to lower the tools *k*, *m* and bring the tool *o* 95 against the rotating insulator blank to produce the desired "neck" part, see Fig. 11. In thus rotating the rod *e*, the arm *q*³ is rotated to the position shown in Fig. 8, while the arm *q*² meets and bears against the front face of the rail *p*, the rail acting as a "stop" 100 to hold the tool *o* in the correct angular position for acting on the insulator blank.

After thus forming the "neck" part the operator rotates the rod *e* and causes the arm *q*³ to pass back through the gap *p*¹ and the tools *k*, *m*, *o* to return to their original 105 at-rest position (see Figs. 1 and 5), ready for the next insulator blank, the arm *q*¹, under the weight of the handle *g*, bearing against the rear face of the rail *p*.

To remove the newly-shaped insulator, the lathe is stopped and the insulator unscrewed by hand, or the motion of the lathe is reversed and the unscrewing of the insulator effected by holding the insulator stationary. 115 For the purpose of giving the tool *k* as little work to do as possible, a small cutter, composed of a taut wire *r* in a frame *r*¹, is hinged to the machine base, see Figs. 1, 2 and 5. Such cutter, just after placing a 120 blank on the screwed part of shaft *b*, is raised by the operator, see Fig. 5, and caused to rapidly remove the major portion of the surplus clay on the top end of the blank to give the blank an approximately flat top, 125 the cutter being afterward lowered and left in the position shown in broken lines in Fig. 5.

The arm q^3 slides against the rear face of the rail p when the tools k and m are brought to the horizontal and are moved endwise to engage the work, see Figs. 6 and 7, the arm q^2 meets and bears against the front face of the rail p when the tool o has effected the full cutting operation, and the arm q^1 meets and bears against the rear face of the rail when the tools k and m are tilted up out of 10 the way, see Figs. 1 and 5.

By the arrangement of tools described and their manipulation in the manner indicated, insulators and the like can be rapidly and accurately shaped by unskilled labor. 15 Further, the tools employed and method of supporting them are such as to call for no delicacy in adjusting them, neither are they such as to be liable to change their position when in operation and spoil the shape of 20 the insulator.

To allow of the position of the tool k being varied to suit insulators of larger or smaller diameter, it is only necessary to slacken the set screws k^3 , move the tool in or 25 out and re-tighten the set screws. The same applies to the tools m , o . Similarly, should a different profile be required, the tools k , m , o are readily removed and new tools substituted. Of course, there may be more than 30 one scalloping tool for effecting the preliminary rough shaping. There may be also two finishing tools k , or a tool o suitable for forming more than one neck or corrugation, or two or more tools o for operating upon 35 different parts of the work. The shaft b will preferably be rotated in the direction of the arrow, Fig. 7, so as to cause the debris to fall below the tool k . To allow for the shaping of insulator blanks, the cylindrical body parts of which require to be of 40 conical formation, the bearing brackets f^1 , f^2 will be carried by a swiveling base part f^3 , see Fig. 4, the said parts being held firmly in position (after being swiveled) 45 by bolts and nuts f^4 . To prevent the rod e rotating while the tools k , m are moving endwise, there may be two rails p^2 , p^3 , see Fig. 4, the arm q^3 being caused to pass between them prior to the rod e being moved 50 endwise to feed the tools k , m against the work.

As shown in Figs. 12 and 13, the sheet metal cutter k , may be replaced by a plate t and a steel blade t^1 , the latter being sharpened on one edge, and being in plan (see Fig. 12) bent to the desired preliminary contour of the intended insulator. The blade t^1 which is secured at each end by set studs u to the ends of the plate t lies at a 55 slight distance from the plate t so as to leave a clearance space t^2 between the blade and plate through which the debris (turnings) may pass during the shaping operation. To

prevent deflection, the blade is stayed along its length by a stay t^3 , which is fastened to 65 the top edge only of the blade, see Fig. 13.

The scalloping tool m , instead of being in the form of a loop, Fig. 9, may be in the form of a half-loop, see Fig. 12.

The tool for "necking" or finally shaping 70 may also be in the form of a scalloping cutter, i , e , it may comprise a plate v and a steel cutter blade v^1 , the latter bent to the intended shape of insulator, and secured at each end to the plate v , which is also shaped 75 so as to leave a clearance space for the debris between itself and the blade. Stays v^2 , v^3 serve to hold the blade against deflection.

In this form of "necking" or finishing tool, the plate v may carry a small edge 80 trimmer v^3 for rounding off the end of the skirt part of the insulator simultaneously with the "necking" of the head part of the insulator. Such edge trimmer will be adjustably held in position by a clamping 85 block w and bolt and nut x .

What I claim is:—

1. In apparatus for externally shaping clay in the manufacture of telegraph insulators and the like, the combination with a 90 rotary shaft adapted to hold and rotate the work during the shaping operations, of a sliding and revoluble rod and a series of tools, adjustably mounted upon the said rod, two of said tools operating upon the clay 95 successively by being moved endwise, and the other tool or tools operating upon the clay after the other tools have completed their work by being fed against the work in the arc of a circle, a fixed rail alongside 100 and parallel with the sliding rod, said rail having a gap in its upper edge, arms on the sliding rod adapted to bear against the said rail and thereby limit the angular movements of the rod and tools, as well as guide 105 the rod and tools when moved endwise, and one of said arms also being adapted to pass through the gap in the rail when brought opposite thereto, as set forth.

2. In apparatus for externally shaping 110 clay in the manufacture of telegraph insulators and the like, the combination with a rotary shaft adapted to hold and rotate the work during the shaping operations, of a sliding and revoluble rod, a profiling tool 115 secured to said rod for imparting a preliminary profiling to the work, a further tool also secured to the said rod and lying in advance of the said profiling tool for removing the excess clay preparatory to the said profiling tool operating upon the work, the two tools operating upon the work under the endwise movement of the rod, two further tools upon the said rod, one for imparting a finished profiling to the work from end to 120 end, and the other for trimming the wider

end of the work, the tools operating upon the work by the said rod being rotated through the arc of a circle, a fixed rail alongside and parallel with the sliding rod and having a gap in its upper edge, arms on the sliding rod, adapted to bear against the said rail and thereby limit the angular movements of the rod and tools, as well as guide the rod and tools when moved endwise,

and one of said arms also being adapted to 10 pass through the gap in the rail when brought opposite thereto, as set forth.

In witness whereof, I have hereunto set my hand in the presence of two witnesses.

WILLIAM PODMORE.
